UNITED STATES PATENT OFFICE.

ERNEST O. WILLIAMS, OF TALLAHASSEE, FLORIDA.

SHOE OR GLOVE BUTTONER.

SPECIFICATION forming part of Letters Patent No. 438,044, dated October 7, 1890.

Application filed April 7, 1890. Serial No. 347,001. (No model.)

To all whom it may concern:

Be it known that I, ERNEST O. WILLIAMS, a citizen of the United States, residing at Tallahassee, in the county of Leon, State of Florida, have invented a certain new and useful Improvement in Shoe or Glove Buttoners, of which the following is a full, clear, and exact specification.

This invention relates to shoe or glove buttoners which are composed of a wire shank having a closed loop or eye at one end for encircling the button and pulling it through the button-hole.

The object of my invention is to improve the prior device by providing a novel construction, whereby the loop or eye will not catch and tear the edges of the button-holes in pulling the buttons therethrough.

To accomplish this object my invention consists of a shoe or glove buttoner composed of a shank bent at one end portion into a loop having its extremity joined to the body of the shank, and one side member of which loop is rectilinear and in alignment with the shank.

In the drawing exhibiting my invention the figure is a perspective view of my improved shoe or glove buttoner.

In the drawing, the numeral 1 indicates the buttoner-shank, composed of a straight piece of wire having a handle 2 at one end, which in the example shown is formed by bending the wire into ring form. This handle, however, may be otherwise constructed to suit the conditions required.

The end portion of the straight shank, which is opposite the handle end, is bent into an oblong loop or eye 3, having its extremity

4 joined to or abutting against the body of the shank. This loop, instead of being obsolete in outline, as usual in this type of buttoners, has the member at one side rectilinear, as at 5, and arranged in alignment with the straight shank in such manner that the closed loop is thrown to and projects solely from one side of the shank. The object of 45 this peculiar construction is to prevent this rectilinear side of the loop from catching into the edges of the button-holes when pulling the buttons therethrough. Where the loop or eye projects laterally from opposite sides 50 of the buttoner-shank, one of such lateral loop-extensions catches the side edges of the button-holes in buttoning a shoe or button and not infrequently tears the same, while the opposite lateral extensions operate to unduly spread the edges of the button-holes 55 apart, and thereby so distend them as to deface the nice appearance of the article. This objection is avoided by my peculiar construction. 60

Having thus described my invention, what I claim is—

A shoe or glove buttoner composed of a straight shank having one end portion bent into the closed loop eccentric to the shank, 65 with one side rectilinear and in alignment with the shank and its terminal adjacent thereto, and the opposite end formed into a suitable handle, substantially as described.

ERNEST O. WILLIAMS.
